UNITED STATES PATENT OFFICE.

ALEXANDER ROBINSON, OF BENICIA, ASSIGNOR TO BAKER & HAMILTON,
OF SAN FRANCISCO, CALIFORNIA.

BAG-HOLDER.

SPECIFICATION forming part of Letters Patent No. 294,505, dated March 4, 1884.

Application filed November 5, 1883. (No model.)

To all whom it may concern:

Be it known that I, ALEXANDER ROBINSON, of Benicia, county of Solano, and State of California, have invented certain Improvements in Bag-Holders, of which the following description, in connection with the accompanying drawings, is a specification.

The object of my invention is to make a simple, durable, and cheap device for holding bags at the mouth of a spout while being filled. This will be more readily understood by referring to the drawings, in which—

Figure 1 is an elevation; Fig. 2, a plan showing the device ready to receive the bag, and Fig. 3 an elevation showing the bag in position.

The same letters refer to the same or like parts in the different views.

Under and to the spout A is fastened the shaft B, having a hook on either end, and also a pawl or lever, C, resting on the spring or inclined plane D, which is riveted to a boss on the side of the sliding fork E, which slides freely in the guides F, attached to the spout A.

Figs. 1 and 2 represent the device closed or not in use, and show the hooks on the shaft B

to be pointed a little downward, ready to receive the bag.

Fig. 3 shows the bag in position and locked fast by the pawl C, resting upon the boss G. The shaft B is turned by means of the pawl traveling up the inclined plane, as the sliding fork is pulled forward to hold and stretch the front of the bag. When in this position, the larger part of the contents of the bag is in front of the guides F, springing the fork sufficiently to prevent it sliding back by any jar, either in a mill or on a thrashing-machine.

To release the bag, all that is required is to shove the fork back with the hand, as in Fig. 1, and the bag drops from the hooks.

Having thus illustrated and described my invention, what I deem new, and desire to secure by Letters Patent, is—

A bag-holder comprising suitable devices for its support, a sliding fork, E, shaft B, provided with hooks, and the lever or arm C, and the inclined plane D, substantially as set forth.

ALEXANDER ROBINSON.
